T. H. THOMAS
ELECTRIC SIGNAL SYSTEM

1,837,378

Filed April 7, 1927

UNITED STATES PATENT OFFICE

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

ELECTRIC SIGNAL SYSTEM

Application filed April 7, 1927. Serial No. 181,715.

This invention relates to signal systems, and more particularly to an electric signal system adapted for use on railway trains.

The principal object of my invention is to provide a train signal system in which the engineer by operating one switch device may signal in response to a signal received by the engineer and by operating another switch device may at any time transmit a signal to 10 one or more vehicles of the train.

In the accompanying drawings: Fig. 1 is a diagrammatic view of an electric train signal system embodying my invention; and Fig. 2 a section of the circuit controlling 15 plug switch, on the line 2—2 of Fig. 1.

As shown in the drawings, there is provided on each car of the train a buzzer or sound producing device comprising an electromagnet 1 having two magnet coils 2 and 3 and a pivotally mounted armature 4, movable away from the magnet by the spring 5, when the magnet is deenergized, and toward the magnet, when the magnet is energized.

One terminal of each coil 2 and 3 is connected to a single train wire 6 and the other terminal of coil 2 is connected to a wire 7, which leads to a contact finger controlled by a plug switch device comprising a casing 9 having a tapered bore adapted to receive a removable switch plug 10. The switch plug 10 is provided with contact segments 11 and 12.

A manually controlled switch device is provided on each car of the train and comprising 35 a casing 15 in which is slidably mounted a contact member 16 provided with contacts 23 and 24. The contact member 16 is provided with an operating push button 17 and is normally maintained in its upper position, 40 as shown in the drawings, by a spring 27.

On the locomotive, there is provided a manually controlled switch device comprising 45 a casing 45 in which is slidably mounted a contact carrying member 46 having a contact 47, said member being normally held in its upper position by a spring 48. Two buzzers 49 and 50 of the well known type, which operate by making and breaking the electric circuit, are connected in parallel to the train 50 wire 6. The buzzers 49 and 50 are connected

respectively to wires 51 and 53 which lead to contacts in the switch device 45.

The resistance of the winding 2 is greater than the resistance of the winding 3, and the operating characteristics of the buzzer 49 are 55 such that it will not operate in series with the winding 2, but will operate in series with the winding 3. The operating characteristics of the buzzer 50 are such that it will operate when in series with either the winding 2 or 60 the winding 3.

There are many ways, well known in the art, for constructing and adjusting the buzzers, so that they will operate in the above manner, such as by varying the resistances 65 of the windings of the buzzers, by varying the air gap between the magnet and the armature or pole piece of the buzzer, by varying the strength of the armature retracting spring of the buzzer, by varying the number of turns 70 of the windings of the buzzers, or by a combination of two or more of the above.

An additional switch device may be provided similar to the switch device 45 and comprising a casing 18 containing a slidable contact member 19 provided with a contact 20, a spring 21 acting on the member 19 and tending to hold same in its upper position. 75

In operation, a plug 10 is inserted in the switch casing 9 by a trainman on each vehicle 80 of the train where it is desired to receive signals originating with the engineman.

If the engineman wishes to signal a station on the train, he depresses the contact member 46. This opens a circuit from the 85 train wire 6 through the buzzer 49 and wire 51, which circuit is normally connected to a ground 22 through the contact 20 of the switch device 18. The downward movement of the contact member 46 also closes a circuit from 90 train wire 6 through the buzzer 50 and wire 53 to ground at 57.

On cars in which the plug 10 is inserted in the casing 9, a circuit will be completed from the train wire 6, through magnet coil 2, wire 95 7, contact 11 in the plug switch device, wire 34, battery 35, wire 43, contact 12, and wire 39 to ground at 40. The buzzer 50 on the locomotive will then be caused to operate by current supplied through the closed circuit from 100

the source of current 35 on the car, and since the buzzer 50 acts to make and break the circuit, the circuit will likewise be made and broken through the magnet coil 2, so that the 5 armature 4 will be vibrated, due to the alternate energization and deenergization of the magnet 1 and the vibration of the armature serves as a signal on cars in which the plug 10 is inserted.

10 The operation of the buzzer 50 on the locomotive also indicates to the engineman that the apparatus is working properly and that a signal is being given on cars of the train.

When a trainman desires to signal the engineman, he presses down on the button 17 of the switch device 15 and thereby closes a circuit from the ground 40, through contact 23, wire 38, battery 35, wire 34, contact 24, wire 32, magnet coil 3, to train wire 6.

15 The magnet coil 3 is of low resistance as compared with the coil 2 and sufficient current will flow through the buzzer 49 to cause same to operate so as to signal the engineman, the circuit being normally closed from train 25 wire 6 to ground at 22 through the contact 47 of the switch device 45 and the contact 20 of the switch device 18.

The buzzer 49 in operating will make and break the circuit through the magnet coil 3, 30 so that the armature 4 is caused to vibrate and thus indicate to the trainman that a signal is being properly transmitted to the engineman.

It will be noted that a circuit is normally closed through the buzzer 49 and the magnet 35 coil 2 by way of wire 7, contact 11, wire 34, battery 35, wire 43, contact 12 and wire 39 to ground at 40, but the coil 2 is of such high resistance that even though all the plugs 10 on the train should be inserted, there will not be 40 sufficient flow of current through the buzzer 49 to cause same to operate.

It will also be noted that a trainman may signal the engineman by operation of the switch device 15, regardless of whether or not 45 the plug 10 is inserted in the plug switch device 9.

If the trainman has signalled the engineman and the plug 10 is not in place, he may receive a signal from the engineman by holding 50 the button 17 depressed. The engineman may then signal the trainman by depressing the contact member 19, so as to open the circuit from the train wire 6 through the buzzer 49 to ground at 22.

55 The switch 45 could not be satisfactorily used under the conditions set forth, because although when the plunger 46 is depressed, the circuit through the wire 51 is momentarily opened, the circuit is again immediately closed through the line 53 to the ground 57. When, however, the plunger 19 is depressed, the circuit remains open, so long as the plunger is depressed, so that the circuit is definitely deenergized long enough to ensure 60 that the coil 3 will be deenergized and thus

produce a definite pause in the operation of the signal device 1.

The result is that the buzzer 49 will cease to operate and the coil 3 will remain deenergized, so that the armature 4 will stop 70 vibrating. The engineman may thus signal the trainman by alternately depressing and releasing the contact member 19, as will be evident.

A rectifier 60 or other means for preventing 75 the flow of current except in one direction, may be interposed in the circuit wire 34, so that in case the voltage of the battery 35 should be in excess of that on another car, there will be no possibility of a reverse flow 80 of current from the excess voltage car back through the batteries of other cars where the voltage is less.

Having now described my invention, what 85 I claim as new and desire to secure by Letters 90 Patent, is:—

1. In an electric train signal system, a train 95 signal circuit, a source of current connected in said circuit, a signal device on one vehicle of the train having two windings with different resistances and connected in said circuit, means for locally closing the circuit through one winding, a manually operated switch device on said vehicle for closing the circuit through the other winding, an automatic 100 make and break device in said circuit on another vehicle of the train responsive only to current flow through one of said windings, another automatic make and break device in 105 said circuit responsive to current flow through either one of said windings, a manually operated switch device for locally closing the circuit through either of said make and break devices, and another switch device for making and breaking the circuit through one of said 110 make and break devices.

2. In an electric train signal system, a train 115 signal circuit, a source of current connected in said circuit, a signal device having two windings connected in said circuit, one of which is of lower resistance than the other, means for locally closing the circuit through said windings and including said source of current, two automatic circuit make and break devices connected in series with said 120 windings, one of which is responsive only to current flowing through one of said windings and the other responsive to current flowing through either of said windings, and two manually operated switch devices, one for closing the circuit through either of said 125 make and break devices and the other for opening and closing the circuit only through one of said make and break devices.

3. In an electric train signal system, a train 130 signal circuit, a source of current connected in said circuit, a signal device having two windings connected in said circuit, one of which is of lower resistance than the other, means for locally closing the circuit including 135

the source of current through the higher resistance winding, a manually operated switch for locally closing a circuit including the source of current through the other winding, two automatic circuit make and break devices connected in series with said windings, one of said make and break devices being such that it responds to current flow through either winding and the other make and break device being such that it responds only to current flow through the winding having the lower resistance, and two manually operable switch devices, one having positions for locally closing the circuit through either of said make and break devices, and the other for opening and closing the circuit through the make and break device which is responsive only to current flow through the low resistance winding.

20 In testimony whereof I have hereunto set my hand.

THOMAS H. THOMAS.
